Primary Examiner—A. Hugo Word**Assistant Examiner—Eric Watterson****Attorney, Agent, or Firm—Hovey, Williams, Timmons & Collins**[57] **CLAIM**

The ornamental design for a radial arm valve linkage, as shown and described.

DESCRIPTION

FIG. 1 is a left side view of a radial arm valve linkage showing my new design;

FIG. 2 is a right side view thereof;

FIG. 3 is a rear elevational view thereof;

FIG. 4 is a front elevational view thereof;

FIG. 5 is a top plan view thereof; and,

FIG. 6 is a bottom plan view thereof.

The lever is shown broken away in FIGS. 1, 3 and 4 for convenience of illustration, and the shaft is shown broken away in FIGS. 3, 4, 5, and 6 to show indeterminate length.
